Molex Duplex fiber optic connector on p. 9H of Molex catalog No. 980, Mar. 1991.

Primary Examiner—Joel Sincavage
Attorney, Agent, or Firm—Foley & Lardner

[57] CLAIM

The ornamental design for a connector, as shown and described.

DESCRIPTION

FIG. 1 is a front perspective view of a first embodiment of the connector including my new design;

FIG. 2 is a rear perspective view thereof;

FIG. 3 is a top plan view thereof;

FIG. 4 is a front side elevational view thereof;

FIG. 5 is a left elevational view thereof;

FIG. 6 is a bottom plan view thereof;

FIG. 7 is a right side elevational view thereof;

FIG. 8 is a rear elevational view thereof;

FIG. 9 is a front perspective view of a second embodiment of the connector including my new design;

FIG. 10 is a rear perspective view of the embodiment of FIG. 9; and,

FIG. 11 is a top plan view of the embodiment of FIG. 9. The rest of views of the embodiment of FIG. 9 is the same as those of the embodiment of FIG. 1.

The appearance of the connector as seen from the rear, where the cord attaches, forms no part of the claimed design.
